TELEPHONE RECORDING SYSTEM

Charles F. Ffolliott, Batavia, Ill., assignor to Automatic Electric Laboratories, Inc., Chicago, Ill., a corporation of Delaware

Application November 5, 1943, Serial No. 509,027

21 Claims. (Cl. 179—6)

1

The present invention relates to telephone conversation recording systems. More particularly, this invention relates to the recording of telephone conversations conducted over a telephone line, and is especially adapted to making an accurate record of two-way telephone conversations which it is desired to preserve for future reference. The system is arranged to be readily associated with any telephone line, requires no metallic connections therewith, and is controllable by a subscriber to record all or parts of a telephone conversation taking place over a line and in such a manner that the party at the distant point is not advised of such recording.

Briefly, the recording system comprises two phonographic recording mechanisms, suitably controlled by sequence operation apparatus for starting and stopping each recorder at the appropriate intervals to provide continuous recording of a conversation which may extend over a period beyond the capacity of a record. An audio-frequency amplifier is provided for the necessary amplification of speech voltages for proper operation of the respective recorders. There are also provided control switches for starting and stopping the operation of the recording mechanism and associated control and supervisory equipment. Supervisory lamp signals are provided for indicating which recorder is in operation, and for indicating when the recording system is conditioned for operation. The recording system is associated with the desired telephone line merely by placing an inductive device in the form of a pickup coil upon the regular bell box or telephone of the telephone substation. No alterations are required in the regular telephone circuit or its line to associate the recording mechanism with the desired line and it is therefore readily attached to any line with a minimum of effort.

It is an object of the invention to provide a telephone conversation phonograph recording system wherein the record cutters are selected for use in alternate order and are controlled to provide an overlap period wherein both recorders are recording at the same time. Another object of the invention is to provide recording apparatus of the above-mentioned type wherein sequence operation means are controlled by the cutting arms for controlling the motors of the recorders to provide for the alternate use of the recorders and the stopping of the motor which is not in use. Still another object of the invention is to provide means for transmitting pulses by the operation of switching means controlled by

2

the cutting arms to control relay switching means by which the recorder motors are appropriately started and stopped. It is a further object of the invention to provide a coil which is adapted to be placed in inductive relation to the induction coils of the telephone set whereby energy is received for the operation of the recorders. Another object is to provide a combined telephone conversation recording and reproducing system by which a telephone conversation may be recorded and then played back or reproduced upon the telephone line.

Other and further objects of the invention will become apparent upon reference to the following description taken in connection with the accompanying drawings in which,

Fig. 1 illustrates somewhat diagrammatically the apparatus and circuit connections of one embodiment of the invention which employs a motor-driven sequence operation mechanism for controlling the sequential operation of the two recorders;

Fig. 2 illustrates a recording system which includes a motor-driven sequence operation mechanism of modified form;

Fig. 3 illustrates a recording system in which the sequence operation mechanism employs a group of relays for controlling the sequential operation of the recorders; and

Fig. 4 shows somewhat diagrammatically the apparatus and circuit connections of a modified system capable of recording a telephone conversation and of reproducing that conversation on the telephone line.

Referring to Fig. 1 of the drawings, there is illustrated a telephone set T, including a ringer box housing 99, a ringer 105, a condenser 106, and an induction coil 113, a transmitter 107, a receiver 108, and a hook switch 110. The hook switch 110, when operated, completes circuits for connecting the telephone set to the associated line 100 extending by way of an exchange to a distant telephone set.

Associated with the telephone T is a pickup coil 114 which is designed to pick up inductively, when placed in close proximity with the induction coil 113 of the telephone T, the conversation taking place over the line. An audio-frequency amplifier 140 is connected to the pickup coil 114 by the conductors 117, 118 and 119, and functions to amplify voice currents which have been inductively picked up and to transmit the amplified currents over the conductors 116 to a pair of phonograph recorders indicated as 120 and 130.

The recorder 120 includes a turntable motor 125 which drives a turntable 121 upon which a phonograph record 126 is placed. A cutting arm 122 is provided with a lug 123 which engages a switch spring to cause the closure of a pair of contacts 124 when the cutting arm reaches a point near the end of the record 126, that is, a point at which the recording space on the record is substantially filled by the record made by the cutter. The engagement of the contacts 124 completes a circuit for energizing a sequence operation motor 162, which drives a number of cams 151, 154, 157 and 160 of a sequence operation mechanism 150, these cams being arranged to operate their associated springs and contacts to control certain circuits for regulating the recorders 120 and 130 together with a plurality of supervisory lamps.

The recorder 130 is similar in all respects to the recorder 120 and is selected for use upon the completion of the record which has been cut by the recorder 120. This recorder 130 comprises a turntable 131, driven in the direction of the arrow by a motor 135 and adapted to have placed thereon a record 136 adapted to be operated upon by a cutter carried by the cutter arm 132. When the recording space of the record is nearly filled a lug 133 carried by the arm 132 closes the switch contacts 134 which are also connected in the controlling circuit of the sequence operation motor 162. A signal lamp 166 indicates when illuminated that the system is in condition to make recordings and the lamps 167 and 168 indicate which of the recorders have been selected for use.

Considering in more detail the operation of the system, and referring to Fig. 1, the closing of the switch 165 by a subscriber at the telephone set T completes a circuit from an alternating current power supply through the conductors 101 and 102 for energizing the amplifier 140 which is thereby conditioned for use. Also, the closing of the switch 165 completes a circuit for energizing the lamp 166 to indicate that the system is ready for recording a telephone conversation. Upon the closing of the switch 163, after closing the switch 165, a circuit is prepared for both of the turntable motors 125 and 135 and for the signal lamps 167 and 168. With the apparatus in the condition illustrated, but with the switches 163 and 165 closed, the turntable motor 125 will operate in a circuit which may be traced from the power conductor 101 by way of switches 165 and 163, through the motor 125, contacts 153 and 156 in multiple, and back to the other power conductor 102. At the same time, the circuit of the signal lamp 167 is completed to indicate that the motor 125 has started to operate.

In the operation of the recorder 120 to record the conversation taking place over the line 100, the voice currents conducted over the line 100 and passing through the induction coil 113 are inductively picked up by the pickup coil 114 and are transmitted to the amplifier 140 by way of the conductors 117 and 118. The amplifier 140 transmits corresponding voice currents by way of the conductors 116 to both of the cutting arms 122 and 132 in multiple. However, if, as shown, only the recorder 120 is in operation at the time, the conversation will be recorded only by that recorder. A conversation which extends beyond the recording capacity of a record and is to be continued on a second record will for a short period be recorded by both recorders to obviate the possibility of omitting a part of the conversation.

during the change over from one recorder to another.

Assuming that the recorder 120 is in operation and that the cutting arm 122 has reached a point near the end of the record 126, the lug 123 causes the contacts 124 to be engaged to close a circuit for starting the sequence operation motor 162. This circuit may be traced from the supply conductor 102 through the contacts 124 and 158 and the motor 162 to the supply conductor 101. The sequence operation motor 162, through a reduction gear train (not shown), drives the cams 151, 154, 157 and 160 in unison in a clockwise direction. The cam 160, upon rotating a short distance, closes at the contacts 161 in parallel with the contacts 158, and this establishes another circuit for the sequence operation motor 162, thus causing the cams 151, 154, 157 and 160 to continue to rotate through one half of a revolution, even though the contacts 158 are opened immediately after the revolution starts. At the conclusion of one half of a revolution of the cam 160, the contacts 161 are opened to interrupt the circuit for the motor 162 which stops the cams in positions 180 degrees from the positions shown. The contacts 155 were also closed shortly after the cam 154 started to rotate, thereby completing a circuit for operating the turntable motor 135 and thereby driving the recorder 130, so that the conversation is then recorded by the recorder 130 while it still continues to be recorded by the recorder 120. The closing of the contacts 155 also closes the circuit of the signal lamp 168 to indicate that the recorder 130 is operating. The contacts 156 are moved into open position at the beginning of the movement of the cam 154 but the circuit of the motor 125 is maintained by the contacts 153 which do not open until the completion of a half of a revolution of the cam 151. When the circuit of the motor 125 is interrupted at the contacts 153, the signal lamp 167 is extinguished, the lamp 167 being connected in multiple with this motor.

The attendant at the recorders is advised by the condition of the lamps 167 and 168 that the record 126 may be removed and a new record placed upon the recorder 120. In removing the record 126, the arm 122 is moved to the left which allows the contacts 124 to open and interrupt a point in the original circuit for energizing the sequence operation motor 162, which is without effect at this time.

When a conversation being recorded upon the record 136 is to be continued upon the new record on recorder 120, the contacts 134 will be closed by the lug 133 shortly before the record 136 is completely filled, which completes a circuit by way of contacts 159 and the conductors 101 and 102 for again starting the sequence operation motor 162. As described before, the contacts 161 are closed at the commencement of the half revolution of the cams to maintain the circuit of the motor 162 so that this motor continues to drive the associated cams through a second one half revolution during which time both recorders are in operation. The motor 125 is then energized over a circuit including the contacts 156 when the cam 154 starts to rotate. After the cams again come to rest in the position shown, the circuit for energizing the turntable motor 135 is opened at contacts 152 and 155 to terminate the recording by the recorder 130. The signal lamp 168 is simultaneously extinguished and the lamp 167 is at the same time illuminated to indicate, respectively, the stopped and running condi-

tions of the recorders 130 and 120. A new record may then be placed on the turntable 131 and the continued alternate operation of the recorders may be carried on as above described, with an overlap of the recording by the two recorders each time that one recorder nears the end of the operation of filling the recording space of the record mounted upon it.

A dual switch 141 is provided, in the circuit shown in Fig. 1, for causing the operation of both recorders to record an entire conversation simultaneously. When closed, the dual switch 141 completes circuits for both turntable motors 125 and 135. With the system in the condition illustrated, the motor 125 is operated over a circuit including contacts 156 and 153 and the motor 135 is actuated over a circuit including switches 165, 163 and 141 and contacts 156 and 153 in multiple. Should the sequence operation mechanism 150 be resting in a position 180 degrees from that shown, during this dual operation, the motor 135 would be actuated over a circuit including contacts 155 and 152, while the motor 125 would be actuated in circuit with the switches 141, 165 and 163, and the contacts 152 and 155 in multiple. During this dual operation both lamps 167 and 168 are illuminated from the supply conductors 101 and 102 over a circuit including the switch 141 and the contacts 156 and 153 when the system is in the position shown, or the contacts 152 and 155, when the cams are rotated through one hundred and eighty degrees from the position shown.

Referring to Fig. 2 of the drawings, there is shown a modification of the invention in which a telephone line 200 terminates in a telephone set T². A pickup coil 214 is inductively associated with the induction coil 213 of the telephone T² and operates to transmit the telephone conversation to an amplifier 240 over the conductors 217 and 218. The amplifier 240 supplies, by way of the conductors 216, voice currents to operate the two phonographic recorders 220 and 230 which are connected in multiple and provided with control switches 224 and 234, respectively, for controlling a sequence operation mechanism 250.

Sequence operation mechanism 250 is provided to control the turntable motors 225 and 235 of the recorders 220 and 230, as well as the supervisory lamps 291 and 292. This sequence operation mechanism includes a driving motor 260, which is coupled through a speed reducing gear (not shown) to a pair of cams 258 and 259 which are rotated in unison for operating a number of switch contacts. Power for operating the sequence operation mechanism 250 and the turntable motors is derived from a source of alternating current through the supply conductors 201 and 202. A signal lamp 290 indicates, when lighted, that the system is operating, and the signal lamps 291 and 292 indicate, respectively, that the recorders 220 and 230 are conditioned for operating. A pair of control switches 265 and 263 are provided for preparing the system for use, and for starting the turntable motor of the recorder which is conditioned to start recording.

Considering in more detail the operation of the system shown in Fig. 2 of the drawings, the closing of the switch 265 completes an obvious circuit for energizing the amplifier 240, which is thereby conditioned for use. At the same time, one or the other of the lamps 291 or 292 will light depending upon which recorder is prepared to operate, and with the apparatus conditioned as illustrated, the lamp 291 is lighted over a circuit

which includes the conductor 202, control switch 265, lamp 291, contacts 252 and 253 in multiple, and the conductor 201. With the lamp 291 illuminated, the subscriber is notified that the recorder 220 is selected to record the conversation taking place over line 200. Upon closing the switch 263 the circuit for the turntable motor 225 is completed; this circuit may be traced from the conductor 202, by way of the switches 265 and 263, through the motor 225 and contacts 252 and 253 in multiple to the conductor 201. The signal lamp 290 is also lighted when the switch 263 is operated to closed position to indicate that the system is recording the telephone message. Voice currents conducted over the line 200 and passing through the induction coil 213 are inductively picked up by the pickup coil 214 and are transmitted therefrom to the amplifier 240 by way of the conductors 217 and 218. The amplifier 240 transmits voice currents over the conductors 216 to the cutting arms 222 and 232 in multiple, so that they may be recorded by either recorder 220 or 230.

A conversation which extends beyond the recording capacity of the record 226 and is to be continued upon the record 236 will, for a short period prior to the time when the cutter reaches the end of the recording space of the record 226, be recorded upon both records. When the cutting arm 222 reaches a point near the end of the record 226, the lug 223 causes the contacts 224 to engage, and thereby close, a circuit for actuating the sequence operation motor 260. This circuit may be traced from conductor 201, by way of the contacts 224 and 256, through the motor 260 and back to conductor 202. The motor 260 then operates and drives the cam 259 which, when it starts to rotate, closes the contacts 257, and thereby establishes an alternate circuit for the motor 260 which causes the cams to be driven through one half of a revolution before they are stopped. At the conclusion of one half of a revolution of the cam 259, the contacts 257 are opened to interrupt the circuit for the motor 260, and as the contacts 256 are also then disengaged, the motor 260 is stopped.

The cam 258, upon rotating a short distance, causes the contacts 251 to be engaged and close a circuit for the turntable motor 235, which circuit includes the conductor 201, contacts 251, the motor 235 and the switches 263 and 265 in series to the conductor 202. The turntable motor 235 starts and drives the recorder 230 while the recorder 220 continues to operate, the circuit for motor 225 being maintained for the duration of the half revolution of cam 258 by the closed contacts 253. When the cam 258 reaches a position approximately 180° from that shown, the contacts 253 are opened to interrupt the circuit for the motor 225, which stops the recorder 220 and extinguishes the signal lamp 291. The contacts 254 are then closed to complete a multiple circuit for continuing the actuation of the motor 235 and the lamp 292, this lamp indicating that the recorder 230 is in operation.

The attendant at the recorders is notified, by the condition of the lamps 291 and 292, that the record 226 may be removed from the recorder 220 and a new record be placed upon the turntable 221. In removing the record 226, the cutting arm 222 is moved to the left, thereby allowing the contacts 224 to be disengaged. The contacts 224, upon opening, interrupt the original circuit for the motor 260.

When a conversation being recorded upon the

record 236 is to be continued upon the new record on the recorder 220, the contacts 234 will be closed shortly before the record 236 is completely filled, thereby completing a circuit by way of the contacts 255 for again actuating the sequence operation motor 260. As described before, the motor 260 drives the cams 258 and 259 one half of a revolution, during which time both recorders are in operation. The motor 225 is then actuated, when cam 258 starts to rotate, over a circuit which includes the power conductor 201, the contacts 252, the motor 225 and the switches 263 and 265 in series to the power conductor 202. After the cams 258 and 259 again come to rest in the position shown in the drawing, the circuit for actuating the motor 235 is opened at the contacts 254, since the contacts 251 were opened when the cam 258 started to rotate. Also, the signal lamp 292 is extinguished when the motor 235 is stopped, since the lamp 292 is connected in multiple with the motor 235. The signal lamp 291 is lighted upon completion of its circuit at the contacts 252 to indicate that the recorder 220 is in operation. From this point the continued alternate operation of the recorders is the same as described above. The same overlap of recording obtains in the change-over period from the recorder 230 to the recorder 220 as prevailed in the change from the recorder 220 to the recorder 230, due to the fact that the contacts 252 and 254 are closed during the one half revolution of cam 258.

A dual switch 241 is provided for causing the operation of both recorders to record the conversation simultaneously. When closed, the dual switch 241 completes circuits for both of the turntable motors 225 and 235. With the system in the condition illustrated, the motor 225 is energized over a circuit including the conductor 202, the switches 265 and 263, the contacts 252 and 253 in multiple and the conductor 201, and the motor 235 is energized over a circuit which includes the switches 265, 263 and 241 and the contacts 252 and 253 connected in multiple to the conductor 201. Should the cams of the sequence operation mechanism 259 be resting in positions 180° from those shown, the motor 235 would be actuated over a circuit including the conductor 202, the switches 265 and 263, the contacts 251 and 254 connected in multiple to the conductor 201. The motor 225 would be actuated over a circuit which includes the conductor 202, the switches 265, 263 and 241, and the contacts 251 and 254 connected in multiple to the conductor 201. During this dual operation both signal lamps 291 and 292 are illuminated by circuits connected in multiple with their respectively associated motors.

Referring to Fig. 3 of the drawings, there is illustrated another modification of the invention comprising the usual telephone set T³ terminating a telephone line 300. The telephone set also includes a ringer 305, a condenser 306, a transmitter 307, a receiver 308, a hook switch 310, and an induction coil 313. Associated with the telephone T³ is a pickup coil 314 which is arranged in inductive relationship to the induction coil 313 to pick up a telephone conversation being conducted over the line 300, and to transmit that conversation to an amplifier 340 over the lines 317 and 318. The amplifier 340 supplies, by way of conductors 316, voice currents to operate the two phonographic recorders 320 and 330 which are connected in multiple. The recorders 320 and 330 are provided with control switches for controlling a sequence operation mechanism 350.

The sequence operation 350 is provided to con-

7
8
trol the turntable motors 325 and 335 of the recorders 320 and 330, respectively, and also to control the supervisory or signal lamps 395, 396, 391 and 392. The sequence operation mechanism 350 includes two pairs of interlocking relays, with each pair arranged in such a manner that a first relay of a pair, when energized, operates and locks mechanically. The second relay of each pair, when operated, unlocks the mechanical lock, thereby allowing the first relay to restore.

A power supply system for furnishing the required alternating current for operation of the amplifiers 340, the turntable motors 325 and 335 and the signal lamps 395, 396, 390, 391 and 392, is connected to the circuits of the recording apparatus by conductors 301 and 302. An auxiliary power supply 341, including a transformer 342 and a rectifier 343, is provided for furnishing rectified current to the relay devices in the sequence operation mechanism 350.

At the telephone set T³ is a control box which includes a power switch 365, for controlling the power to the amplifier 340 and to the lamp 390, and a motor switch 363 for controlling the power to the turntable motors 325 and 335, to the auxiliary power supply 341, and to the signal lamps 391, 392. The control box also includes the signal lamps 390, 391 and 392. The lamps 395 and 396 are located at the recording devices and are provided for the purpose of advising an attendant of the operating or restored condition of the two recorders.

Considering in more detail the operation of the system in reference to Fig. 3 of the drawings, the closing of the switch 365 completes a circuit for energizing the amplifier 340 and the multiple connected lamp 390. Circuits are also prepared at the switch 365 for actuating the lamps 395 and 396 and, dependent upon which recorder is conditioned for use, the corresponding lamp circuit is completed. That is, when recorder 320 is selected for use, the lamp 396 will be illuminated over a circuit which includes the conductor 301, switch 365, lamp 396, contacts 382 and the conductor 302. If, however, the recorder 330 has been selected, the lamp 395 is lighted over a circuit including the conductor 301, switch 365, lamp 395, contacts 382 and the conductor 302.

Upon operation of the motor switch 363, circuits are completed for the auxiliary power supply 341, and the turntable motor 325 together with the signal lamp 391. The circuit for the motor 325 extends from the conductor 301 by way of switches 365 and 363 through the motor 325 and contacts 382 to conductor 302. The lamp 391 is energized over a circuit which includes the switches 365 and 363, the contacts 384 and the power conductors 301 and 302.

Relay 380 is shown mechanically locked in an operated position whereby the recorder 320 is selected to record a telephone conversation taking place over the line 300. Voice currents conducted over the line 300 and passing through an induction coil 313 are inductively picked up by the pickup coil 314 and the amplifier 340 transmits the amplified voice currents over the conductors 316 to the cutting arms 322 and 332. However, as only the recorder 320 is at present assumed to be in operation, the conversation will be recorded only by that recorder.

A conversation which extends over the recording capacity of the record 326, and is to be continued upon the record 336, will for a short time prior to the end of the record 326 be recorded upon both records. When the cutting arm 322

reaches a point near the end of the record 326, the lug 323 first causes the contacts 324 to engage and close a circuit for energizing the relay 370. This circuit may be traced from the terminal 346 of the auxiliary power supply 341 by way of the conductor 344, contacts 324, 372, 386 and 385 through the winding of the relay 370 and conductor 345 to the opposite pole 347 of the auxiliary power supply 341. The relay 370 operates and is held operated over a circuit extending from the terminal 346 through the contacts 324 and 371 and the winding of relay 370 and to the terminal 347. Also, the relay 370, in operating, unlocks the mechanically locked relay 380.

Relay 380 then restores and, at contacts 381, completes a circuit for starting the turntable motor 335, which includes the conductor 302, the contacts 381, the motor 335, the switches 363 and 365, and the conductor 301. Both recorders 320 and 330 will record the conversation simultaneously until the cutting arm 322 reaches a point where the lug 323 next causes the contacts 327 to engage, when a circuit is completed for energizing the relay 350. It is observed that the circuit for the motor 325 was not broken when the relay 380 restored, as a multiple path extending through the contacts 351 maintained an operating circuit for the motor 325 during the change-over period. The relay 350 operates and opens at the contacts 351 the circuit for the motor 325 which stops the recorder 320; also, the relay 350 completes at the contacts 352 a multiple path for energizing the motor 335.

When the relay 380 has restored and the relay 350 has operated, the circuit for illuminating the signal lamp 396 is interrupted at the contacts 382 and 351 to extinguish this lamp and thereby notify the attendant at the recorders that the recorder 320 has stopped and that a new record may be placed thereon. Likewise, with the relay 380 restored and the relay 350 operated, the lamp 395 is lighted in a circuit including the contacts 381 and 352 in multiple and the conductors 301 and 302 in series with the switch 365. The lamp 395, when lighted, advises the attendant that the recorder 330 is in use.

In the control box, the lamp 391 is extinguished when the relay 380 restores and the relay 350 operates, since the circuit for the lamp is then interrupted at the contacts 384 and 353. The lamp 392 is illuminated over multiple circuits including the contacts 383 and 354, the power conductors 301 and 302 and the switches 363 and 364. These lamp signals advise the subscriber of the resting and operating conditions of the respective recorders 320 and 330. Before removing the record 326 from the turntable 321, the cutting arm 322 is moved to the left, which allows the contacts 324 and 327 to open and interrupt the holding circuits for the relays 370 and 350, respectively. The relay 370 restores but the relay 350 remains operated due to the mechanical interlock thereon.

The recording may be terminated by moving the switch 363 to its open position, thereby interrupting the circuits for supplying power to the lamps 391 and 392, the motors 325 and 335, and the auxiliary power supply 341. The amplifier 340 remains energized together with the signal lamp 390, which lamp indicates that the system is ready for operation. The switch 365, when opened, disconnects all of the apparatus of the system from the power conductor 301.

When a conversation being recorded upon the record 336 is to be continued upon the new record placed upon the recorder 320, and as the cutting

arm reaches a point where the lug 333 first causes the contacts 334 to close, a circuit is completed for energizing the relay 360. The relay 360 is energized over a circuit traced from the terminal 347 of the auxiliary power supply 341, through the winding of the relay 360, and the contacts 355, 356, 362 and 334 to the terminal 346. Upon operating, the relay 360 completes a holding circuit including the contacts 361 and 334, and the conductors 344 and 345 for holding itself operated. In operating, relay 360 unlocks the mechanical lock which holds the relay 350 in an operated position, whereupon relay 350 restores. The relay 350, upon restoring, opens at the contacts 352 a point in the operating circuit for motor 335, but this motor continues to drive the recorder 330 since it is supplied with current by another circuit including the contacts 381.

At approximately the time when the end of the recording on the record 336 is reached, the contacts 337 are closed by the lug 333, thereby closing a circuit for the relay 380, extending from the terminal 347 through the winding of relay 380 and the contacts 372 and 337 to the terminal 346 of the auxiliary power supply 341. The relay 380 then operates and is mechanically locked in its operated position. Upon operating, the relay 380 interrupts, at the contacts 381, the circuit for energizing the motor 335, whereupon the recorder 330 is stopped; and, at the same time, the contacts 382 are actuated to close a parallel circuit for motor 325. At the contacts 383, the circuit for the illuminating lamp 392 is opened and at contacts 384 a circuit is completed for lighting the lamp 391; this latter circuit may be traced from the power conductor 301 by way of switches 365 and 363, lamp 391, and contacts 384 to conductor 302. With the lamp 392 extinguished and the lamp 391 lighted, an indication is given of the resting and operating conditions of the respective recorders 330 and 320. Also, the circuit for lighting the lamp 395 is opened at the contacts 352 and 381 while the circuit for illuminating lamp 396 is completed at the contacts 382 and 351, as above described. In transferring from the recorder 330 to the recorder 320, there is the same overlap as prevailed when a transfer was made from the recorder 320 to the recorder 330, the overlap period being determined by the sizes of the gaps 398 and 399.

In Fig. 4 of the drawings, there is illustrated a combined telephone conversation recording and reproducing system by which a telephone conversation may be recorded upon a phonograph record and may, at will, be "played back" upon the associated telephone line. The recording and reproducing mechanism are associated with the line by means of inductive devices in the form of pickup coils which may be placed upon or in the close proximity of the usual bell box or telephone.

There is included in this system a telephone T4 of conventional design terminating the line 400 and having the usual transmitter 407, a receiver 408, and a hook switch 410. Housed in the bell box of this telephone is a ringer 405 and an induction coil 413, the latter being arranged to be effectively connected across the line 400 through the contacts 411 and 412 of a hook switch 410. The pickup coils 415 and 425, when placed upon the bell box, inductively couple the line 400 with the phonograph recording and reproducing arms of a recording device. A three position switch 430, having a plurality of sets of contacts, is provided for selectively connecting the coil 415 or the coil 425 with an amplifier 440 and with the

recording arm 433 and the reproducing arm 434 of the recording and reproducing mechanism which includes a motor 436 for driving a recording turntable 437 upon which is mounted a phonograph disk 435 in the usual manner. The recording arm 433 is provided to cut a record of a telephone conversation and the reproducing arm 434 is provided for reproducing, back over the telephone line, a recorded message. It is contemplated that either of the arms may be operative during a conversational period and, by manipulation of the switch 430, either of the arms may be included in the conversational circuit.

When it is desired to record a conversation taking place over the line 400, the key 441 is closed to complete an obvious circuit for energizing the motor 436 from the source of power 438. The switch 430 is also operated to close its contacts 2 and 3 to complete a circuit, including the conductors 416 and 431, between the amplifier 440 and the recording arm 433. The closing of the contacts 6 and 7 completes a circuit, including the conductors 417 and 418, between the pickup coil 415 and the input terminals of the amplifier 440. Upon then placing the recording arm 433 upon the recording disk 435, a record may be made of any conversation taking place upon the line 400. More particularly, any voice currents that pass through the induction coil 413 are inductively picked up by the pickup coil 415 and are conducted over the conductors 417 and 418 through the contacts 6 and 7 of the switch 430 to the amplifier 440. These voice currents are therein amplified and are extended over the conductors 416 and by way of the contacts 2 and 3 of switch 430 and conductors 431 to the recording arm 433. The recording arm 433 responds to the amplified voice currents to record the conversation upon the disk 435.

When it is desired to reproduce upon the telephone line 400 the conversation recorded on the disk 435, the switch 430 is operated to cause the contacts 2, 3, 6 and 7 to become disengaged from the movable switch contacts and thus open the recording circuits, and to cause the contacts 1, 4, 5 and 8 to be closed to complete the reproducing circuits, which include the reproducing arm 434, the battery or power supply 442, the amplifier 440 and the coil 425. The reproducing arm 434 is energized by the battery 442, and when the arm is placed upon the disk 435, it effectively transmits by way of the conductors 432 and the contacts 5 and 8 of the switch 430, corresponding voice currents to the amplifier 440. The amplifier 440 functions to increase the amplitude of these voice currents and transmits them over conductors 416 and by way of the contacts 1 and 4 of the switch 430 and the conductors 419 and 420 to the coil 425. Responding to the amplified voice currents, the coil 425 creates an inductive field whereby the induction coil 413 is inductively affected to reproduce corresponding voice currents upon the line 400.

From the foregoing it will be seen that at the option of the operator a telephone conversation may be recorded upon a phonograph record or the recorded conversation may be reproduced upon the line, whereby both parties may hear the record, and, further, the recording mechanism may be excluded from the connection entirely by operating the switch 430 to its neutral position.

Although several forms of the invention have been shown and described by way of illustration,

it will be understood that the invention may be constructed in various other embodiments which come within the scope of the appended claims.

I claim:

1. A telephone conversation phonograph recording system comprising, a pickup coil adapted to be positioned in inductive relation to the induction coils of a telephone set, an amplifier connected to said pickup coil, a pair of record cutters energized by said amplifier, a turntable and motor for each cutter, a source of power for said amplifier and said motors, a switch for each turntable adapted to be actuated by said cutter as it approaches the end of a record, and means controlled by said switch for energizing the other motor from said source of power before the end of a record is reached to provide an overlap period wherein both cutters are recording at the same time.
- 15 2. A telephone conversation phonograph recording system comprising, a pickup coil adapted to be positioned in inductive relation to the induction coils of a telephone set, an amplifier connected to said pickup coil, a pair of record cutters energized by said amplifier, a turntable and motor for each cutter, a source of power for said amplifier and said motors, a switch for each turntable adapted to be actuated by said cutter as it approaches the end of a record, and sequence operation means controlled by said switch for energizing the other motor prior to the end of a record to provide an overlap period wherein both cutters are recording at the same time and for deenergizing the first motor when the end of the first record is reached.
- 20 3. A telephone conversation recording system comprising, a pickup coil adapted to be positioned in inductive relation to the induction coils of a telephone set, a pair of record cutters energized in response to energy received by said pickup coil, a record carrying turntable and a motor for each cutter, a switch for each turntable adapted to be actuated by its cutter as it approaches the end of a record, and sequence operation means controlled by said switches for energizing and deenergizing said motors thereby to provide prior to the end of a record an overlap period wherein both cutters are recording at the same time and for deenergizing each motor at the end of the recording on the record carried on the turntable driven thereby.
- 25 4. A telephone conversation phonograph recording system comprising, a pickup coil adapted to be positioned in inductive relation to the induction coils of a telephone set, an amplifier connected to said pickup coil, a pair of record cutters energized by said amplifier, a turntable and motor for each cutter, a switch for each turntable adapted to be actuated by said cutter as it approaches the end of a record, said switch having two sets of contacts one of which closes before the other, and sequence operation means controlled by one set of contacts of said switch for energizing the other motor prior to the end of a record to provide an overlap period wherein both cutters are recording at the same time, and means including said other set of switch contacts for deenergizing the first motor at the end of the first record.
- 30 5. A telephone conversation phonograph recording system comprising, a pickup coil adapted to be positioned in inductive relation to the induction coils of a telephone set, means for making records in accordance with the energy received by said pickup coil including a pair of

record cutters, a turntable and motor for each cutter, a switch for each turntable arranged to be actuated by said cutter as it approaches the end of a record, a pair of interlocking relays for each of said motors to control the operation thereof, the first of each pair of relays having certain contacts locked into position upon energization of said relay, the second of each pair of relays operating to release the contacts of said first relay, said switch having contacts connected to one relay of each pair of relays, said relays operating to energize the other motor prior to the end of a record to provide an overlap recording period and to deenergize the other motor at the end of the record.

6. A telephone conversation recording system comprising, a pickup coil adapted to be positioned in inductive relation to the induction coils of a telephone set, a pair of record cutters energized in response to the energy received by said pickup coil, a turntable and motor for each record cutter, a switch for each turntable adapted to be actuated by its record cutter as it approaches the end of a record, said switch means each operating to transmit two current impulses, one impulse prior to the completion of a record and another impulse at the completion of a record, and means responsive to said pulses for energizing the other motor prior to the end of a record to provide an overlap recording period and for deenergizing the one motor at the end of its record.

7. A telephone conversation recording system comprising, a pickup coil adapted to be placed in inductive relation to the induction coils of a telephone set, means for producing a record in accordance with the energy received by said coil including a pair of record cutters, a turntable and motor for each cutter, a switch for each turntable adapted to be actuated by its cutter as it approaches the end of a record, and sequence operation means controlled by said switches for controlling the operation of said turntable motors including a sequence operation motor connected to a plurality of groups of cam operated switches, one of said groups of cam operated switches operating to energize both turntable motors prior to the end of a record to provide an overlap recording period and to stop one turntable motor when the end of a record has been reached, and another group of cam operated switches operating to switch the control of said sequence operation motor from one turntable switch to the other turntable switch near the end of the record.

8. A telephone conversation recording system comprising, a pickup coil adapted to be placed in inductive relation to the induction coils of a telephone set, means for producing a record in accordance with the energy received by said coil including a pair of record cutters, a turntable and motor for each cutter, a switch for each turntable adapted to be actuated by its cutter as it approaches the end of a record, and sequence operation means controlled by said switches for controlling the operation of said turntable motors including a sequence operation motor connected to a plurality of groups of cam operated switches, one of said groups of cam operated switches operating to energize both turntable motors prior to the end of a record to provide an overlap recording period and to stop one turntable motor when the end of a record has been reached, and another group of cam operated switches operating to switch the control of said sequence operation motor from one turntable switch to the other turntable switch near the end of the record.

ord, and a manually operable switch for causing both turntable motors to be operated at the same time.

9. A telephone conversation recording system comprising, a pickup coil adapted to be placed in inductive relation to the induction coils of a telephone set, means for producing a record in accordance with the energy received by said pickup coil including a pair of record cutters, a turntable and motor for each cutter, a source of power, a power switch for connecting certain of said equipment to said source to condition said equipment for operation, a second power switch connected between said source and said motors, a switch for each turntable adapted to be actuated by its cutter as it approaches the end of a record, sequence operation means controlled by said switches for determining the operation of said turntable motors including a sequence operation motor connected to a plurality of groups of cam operated switches, one of said groups of cam operated switches operating to energize both turntable motors prior to the end of a record to provide an overlap recording period, another group of said cam operated switches operating to switch the control of said sequence operation motor from one turntable switch to the other turntable switch near the end of a record, and a third set of cam operated switches preparing a visual signal system to indicate which motor will start first upon actuation of said second power switch.

10. A telephone conversation recording system comprising, a pickup coil adapted to be placed in inductive relation to the induction coils of a telephone set, means for producing a record in accordance with the energy received by said coil including a pair of record cutters, a turntable and motor for each cutter, a source of power, a power switch for connecting certain of said equipment to said source to condition said equipment for operation, a second power switch connected between said source and said motors, a switch for each turntable adapted to be actuated by its cutter as it approaches the end of a record, sequence operation means controlled by said switches for determining the operation of said turntable motors including a sequence operation motor connected to a plurality of groups of cam operated switches, one of said groups of cam operated switches operating to energize both turntable motors prior to the end of a record to provide an overlap recording period, another group of said cam operated switches operating to switch the control of said sequence operation motor from one turntable switch to the other turntable switch near the end of a record, and a third set of cam operated switches preparing a visual signal system to indicate which motor will start first upon actuation of said second power switch.

11. A telephone conversation recording system comprising, a pickup coil adapted to be placed on the exterior of a telephone set in inductive relation to the induction coils of said telephone set, means including an amplifier for producing a record in accordance with the energy received by said pickup coil including a pair of record cutters, a turntable and motor for each cutter, a source of power, a power switch for connecting said amplifier to said source, a second power switch interconnecting said source and said turntable motors, a switch for each turntable adapted to be actuated by its cutter as it ap-

proaches the end of a record, sequence operation means controlled by said turntable switches for controlling the said sequence operation means including a sequence operation motor connected to a plurality of groups of cam operated switches, one of said groups of cam operated switches operating to control the operation of said turntable motors and to energize both turntable motors prior to the end of a record to provide an overlap recording period near the end of a record on one of said turntables, another group of said cam operated switches operating to change the control of said sequence operation motor from one turntable switch to the other turntable switch as the cutter approaches the end of a record, a third set of cam operated switches being adapted to control a signal light system, a signal circuit including said third set of cam operated switches and a plurality of signal lights for indicating which motors are being energized.

12. In a system for recording telephone conversation at a telephone subscriber station including a telephone set having an induction coil, the combination of means for producing a record in accordance with a telephone conversation, and means for receiving energy from the telephone set to control the actuation of said first-named means, said second-named means comprising a coil adapted to be placed on the outside of said telephone set in inductive relation to the induction coil of said telephone set.

13. The combination with a telephone set having an induction coil of a telephone conversation recording and reproducing system comprising, a pickup coil adapted to be positioned in inductive relation to said induction coil, an amplifier arranged to be connected to said pickup coil, a record cutter energized by said amplifier, a turntable for supporting a record in operative relation to said cutter, a motor for driving said turntable, a reproducing device arranged to be operated by a record on said turntable, power supply means for said amplifier and said reproducing device, and means for controlling the operation of said cutter and said reproducing device.

14. The combination with a telephone set having an induction coil of a telephone conversation recording and reproducing system comprising, a pickup coil adapted to be positioned in inductive relation to said induction coil, an amplifier arranged to be connected to said pickup coil, a record cutter energized by said amplifier, a turntable for supporting a record in operative relation to said cutter, a motor for driving said turntable, a reproducing device arranged to be operated by a record on said turntable, power supply means for said amplifier and said reproducing device, means for controlling the operation of said cutter and said reproducing device, and a second pickup coil arranged to be connected in the circuit with said reproducing device and said amplifier and adapted to be placed in inductive relation to said induction coil.

15. In a sound recording system the combination comprising at least two recording machines for recording sounds on records, means controlled by each machine for starting another machine when the record of the former is substantially full, means controlled by each machine for stopping it a predetermined period of time after it has started another machine, a first control for starting and stopping an operating machine, and a second control for connecting the first control to two or more machines whereby duplicate records of the same dictation may be made.

16. In the combination of 15, means also controlled by each machine for transferring the first control to each machine as it is started by another.

5. 17. In an electro-acoustic system the combination including a recording machine having a rotatable record support, a recording head for cooperating with the record when mounted on said support, driving means for causing relative movement between said support and recording head, a power circuit for said driving means, a control station remote with respect to said recording machine, a microphone, circuits interconnecting the microphone with the recording head, a marking control switch at the control station for partially completing said power circuit, and a start-stop switch at the control station for completing the power circuit to said driving means.

10. 18. In an electro-acoustic system the combination including a recording machine having a rotatable record support, a recording head for cooperating with the record when mounted on said support, driving means for causing relative movement between said support and recording head, a power circuit for said driving means, a control station remote with respect to said recording machine, a microphone, circuits interconnecting the microphone with the recording head, a marking control switch at the control station for partially completing said power circuit, and a start-stop switch at the control station for completing the power circuit to said driving means.

15. 19. In an electro-acoustic system the combination including a recording machine having a rotatable record support, a recording head for cooperating with the record when mounted on said support, driving means for causing relative movement between said support and recording head, a power circuit for said driving means, a control station remote with respect to said recording machine, a microphone, circuits interconnecting the microphone with the recording head, a marking control switch at the control station for partially completing said power circuit, and a start-stop switch at the control station for completing the power circuit to said driving means.

20. 20. In an electro-acoustic system the combination including a recording machine having a rotatable record support, a recording head for cooperating with the record when mounted on said support, driving means for causing relative movement between said support and recording head, a power circuit for said driving means, a control station remote with respect to said recording machine, a microphone, circuits interconnecting the microphone with the recording head, a marking control switch at the control station for partially completing said power circuit, and a start-stop switch at the control station for completing the power circuit to said driving means.

25. 21. In an electro-acoustic system the combination including a recording machine having a rotatable record support, a recording head for cooperating with the record when mounted on said support, driving means for causing relative movement between said support and recording head, a power circuit for said driving means, a control station remote with respect to said recording machine, a microphone, circuits interconnecting the microphone with the recording head, a marking control switch at the control station for partially completing said power circuit, and a start-stop switch at the control station for completing the power circuit to said driving means.

30. 22. In an electro-acoustic system the combination including a recording machine having a rotatable record support, a recording head for cooperating with the record when mounted on said support, driving means for causing relative movement between said support and recording head, a power circuit for said driving means, a control station remote with respect to said recording machine, a microphone, circuits interconnecting the microphone with the recording head, a marking control switch at the control station for partially completing said power circuit, and a start-stop switch at the control station for completing the power circuit to said driving means.

35. 23. In an electro-acoustic system the combination including a recording machine having a rotatable record support, a recording head for cooperating with the record when mounted on said support, driving means for causing relative movement between said support and recording head, a power circuit for said driving means, a control station remote with respect to said recording machine, a microphone, circuits interconnecting the microphone with the recording head, a marking control switch at the control station for partially completing said power circuit, and a start-stop switch at the control station for completing the power circuit to said driving means.

19. 24. In an electro-acoustic machine of the type described the combination including a rotatable record support, a sound recording head, driving means for causing relative movement between said support and head, drive control means for controlling the starting and stopping of said driving means including a start-stop switch, a power circuit for said drive control means, and a marking control switch for partially completing said power circuit, successive operation of said start-stop switch causing successive energization of said driving control means to cause the starting and stopping of the machine.

40. 25. In an electro-acoustic machine of the type described the combination including a rotatable record support, a sound recording head, driving means for causing relative movement between said support and head, drive control means for controlling the starting and stopping of said driving means including a start-stop switch, a power circuit for said drive control means, a marking control switch for partially completing said power circuit, successive operation of said start-stop switch causing successive energization of said drive control means to cause the starting and stopping of the machine, a signal lamp, and a power circuit for said lamp completed when said marking control switch is first operated.

45. 26. In an electro-acoustic machine of the type described the combination including a rotatable record support, a sound recording head, driving means for causing relative movement between said support and head, drive control means for controlling the starting and stopping of said driving means including a start-stop switch, a power circuit for said drive control means, a marking control switch for partially completing said power circuit, successive operation of said start-stop switch causing successive energization of said drive control means to cause the starting and stopping of the machine, a signal lamp, and a power circuit for said lamp completed when said marking control switch is first operated.

50. 27. In an electro-acoustic machine of the type described the combination including a rotatable record support, a sound recording head, driving means for causing relative movement between said support and head, drive control means for controlling the starting and stopping of said driving means including a start-stop switch, a power circuit for said drive control means, a marking control switch for partially completing said power circuit, successive operation of said start-stop switch causing successive energization of said drive control means to cause the starting and stopping of the machine, a signal lamp, and a power circuit for said lamp completed when said marking control switch is first operated.

55. 28. A system for controlling the operation of a dictation machine, including a movable record support, a recording head, a reproducing head, said heads being independently engageable with a record on said support, a single manual means remote with respect to said machine controllable only for starting and for stopping it, and a single manual means at the remote point controllable only for rendering either the

recording head or the reproducing head operative.
